UNITED STATES PATENT OFFICE.

JOHN H. STONE, OF EDGEWOOD, RHODE ISLAND.

HAIR COMB.

Application filed February 21, 1922. Serial No. 538,351.

To all whom it may concern:

Be it known that I, JOHN H. STONE, a citizen of the United States, residing at Edgewood, in the county of Providence and 5 State of Rhode Island, have invented certain new and useful Improvements in Hair Combs, of which the following is a specification.

This invention relates to a new means 10 for mounting a string of beads or pearls in a supporting member, and the object of this invention is to string a series of beads upon a short length of wire and to secure the ends of the wire in the supporting member such 15 as an ornamental hair comb or other device, by means of which the beads are locked on the wire and the whole is connected to the support.

With these and other objects in view, the 20 invention consists of certain novel features of construction, as will be more fully described, and particularly pointed out in the appended claims.

In the accompanying drawings:

25 Figure 1 is a side elevation of an ornamental hair comb ornamented by the mounting of several strings of beads therein by my improved means.

Figure 2 is a detail showing one of the 30 short lengths of wire removed.

Figure 3 is a detail of one of the pearls or beads.

Figure 4 is a sectional side elevation illustrating the method by means of which the 35 ends of the wire on which the beads are strung is bent and snapped into the holes or sockets in the end portions of a comb or other supporting member.

Figure 5 shows the wire as having been 40 released to spring back into normal shape thereby forcing its ends into the sockets formed to receive them thus locking the beads securely on the wire and at the same time securing the whole to the support.

45 It is found in practice to be very desirable in ornamental hair combs and other devices, to provide a comb with one or more narrow openings through it and in these openings to mount a series or string of 50 pearls or beads, and the following is a detailed description of one means by which this mounting of the beads or pearls may be effected.

With reference to the drawings 10 designates the ornamental supporting member

which in this particular case is shown to be an ornamental hair comb and this comb is provided with the usual teeth 11 by which it is secured to the hair of the wearer.

The exposed portion 12 of this comb is 60 shown as being provided with one or more vertically-disposed, narrow openings 13 through it which openings may be made on the arc of a circle if desired or in any other suitable or artistic shape to lend grace and 65 beauty to the exposed portion of the comb.

It is found in practice very desirable to 70 mount a series or string of beads 14 in each of these recesses or openings 13 and to do this in a simple and effective way I have 75 drilled or otherwise formed holes or sockets 15 and 16 in the stock of the body of the comb in the walls at the opposite ends of these recesses or openings, care being taken 80 not to form the hole or opening from the inside through to the outside edge of the comb body for the reason presently described. I then take a length of wire 9 of a diameter adapted to pass through the eyes 85 of the different beads which are preferably graduated in size and string the beads upon the wire permitting the ends of the wire to project beyond the end beads of the string, the wire being of a length to extend beyond the end beads to engage the openings 15 and 16 in the comb.

In order to position this string of beads I 90 now bend the length of wire, best illustrated in Figure 4, and which is preferably formed of spring stock and place one of its ends in its socket 15 and when released the wire 95 will have a tendency to return to its normal shape and stand in the center of the opening as best illustrated in Figure 5, whereby the stock of the comb at the ends of the recess 13 serves to now lock the beads or pearls firmly onto the wire and also to lock the whole string and the wire firmly into the body of the comb greatly enhancing the beauty and 100 attractiveness of the comb as an ornament.

In practice it is found to be undesirable to 105 drill the hole 15 way through to the outside of the stock for two reasons first, the hole on the outside is unsightly; and second, the wire might work outward through the hole to release the pearls permitting them to become lost.

The foregoing description is directed 110 solely towards the construction illustrated, but I desire it to be understood that I re-

serve the privilege of resorting to all the mechanical changes to which the device is susceptible, the invention being defined and limited only by the terms of the appended 5 claims.

I claim:

1. An ornamental comb having an opening therein, recesses in the walls of the opening, a series of beads strung upon a length 10 of wire, the ends of the wire projecting beyond the end beads of the string and secured in said recesses whereby the beads are locked on the wire and the whole in said comb.
2. An ornamental device having slots 15 therein, short lengths of resilient wire, a series of beads strung upon each wire, the ends of the wire extending beyond the end beads of the string, said slots being provided with recesses into which the ends of each 20 wire are set to lock the beads on the wire and connect the whole to said device.
3. An ornamental comb having openings therein and recesses in the end walls of the openings, a plurality of short lengths of re-

silient wire, a series of beads strung upon 25 each wire, the ends of each wire projecting beyond the end beads of the string and adapted to be bowed to spring its ends into the recesses at the ends of each opening to lock the beads onto the wire and the whole 30 in an opening of said support.

4. An ornamental device having a series 35 of slots in it and a hole in each of the end walls of said slots, a string of beads inserted into each of said slots, each string comprising a series of beads strung upon a short length of resilient wire having its ends projecting beyond the end beads thereof, said wire being adapted to be 40 sprung or bowed to permit its ends to be snapped into said holes whereby the beads are locked onto the wire and the whole retained in its slot, the resiliency of the wire permitting the string to follow the contour 45 of the slot.

In testimony whereof I affix my signature.

JOHN H. STONE.
